UNITED STATES PATENT OFFICE.

FREDRICK D. BOWEN AND SAMUEL T. CLUTTER, OF MONETT, MISSOURI.

VALVE.

1,119,060.

Specification of Letters Patent.

Patented Dec. 1, 1914.

Application filed February 3, 1914. Serial No. 816,217.

To all whom it may concern:

Be it known that we, FREDRICK D. BOWEN and SAMUEL T. CLUTTER, citizens of the United States, residing at Monett, in the county of Barry and State of Missouri, have invented certain new and useful Improvements in Valves, of which the following is a specification, reference being had therein to the accompanying drawing.

10 The invention relates to improvements in valves and the primary object of the invention is to provide an improved valve construction designed more especially for use in connection with gas heating and lighting systems, and adapted to permit a free distribution of gas or other fluid when the pressure in the system is maintained up to the normal or predetermined degree and capable, should the pressure diminish, of 20 automatically closing and entirely cutting off the flow, and of remaining in closed position until manually reset, whereby the escape of gas at the burners and other appliances resulting from the irregular supply 25 of gas to the system will be prevented.

The invention also aims to provide an improved safety device of this nature, which will be simple and inexpensive in construction, efficient in use and adapted to be conveniently connected to gas distributing systems or the like.

30 The invention will be clearly understood from the following detailed description when considered in connection with the accompanying drawings forming a part hereof and illustrating one embodiment of the invention.

In the drawings: Figure 1 is a top plan view, Fig. 2 is a longitudinal section taken 40 on the line 2—2 of Fig. 1, showing in full lines the valve in closed position and indicating in dotted lines the valve in open position, Fig. 3 is a transverse section on the line 3—3 of Fig. 2 looking in the direction 45 of the arrow.

Referring to the drawing in detail, which 50 illustrates a preferred embodiment of the invention and in which like reference characters designate corresponding parts throughout the several views, 1 designates a casing divided by a substantially horizontal partition wall 2 into an upper chamber 3 and a lower chamber 4.

55 5 designates a tubular inlet leading to the upper chamber 3 and 6 a tubular outlet

leading from the lower chamber 4, said inlet and outlet being shown in the drawings as integral extensions of the casing, an opening 7 being provided in the partition wall 2 to afford a passage for the gas or other fluid from the upper to the lower chamber. The tubular inlet 5 is inwardly extended to form with the partition wall 2 an inner guide 8 for a reciprocating valve 9. The valve is shown in the drawing as 60 substantially cylindrical in shape with a flattened upper face which is adapted to engage the upper wall 9' of the valve guide 8, said upper wall being correspondingly flattened, this construction serving to prevent the valve from turning. The valve, which is preferably hollow and constructed of aluminum has a reduced tapered outer portion 10, and a valve seat is provided by a bushing 11 fitted within and in threaded 65 engagement with the tubular inlet 5, said bushing being interiorly tapered to correspond with the tapered portion 10 of the valve, the valve being adapted to coact with the seat to cut off communication between 70 the inlet 5 and the outlet 6. A gasket of rubber or other suitable material is interposed between the inner end of the bushing and an inwardly extending angular shoulder 12, to provide a gas tight joint between 75 the bushing and the wall of the inlet. A coiled spring 13 acts to force the valve to its seat, said spring being positioned with one end bearing against the rear end of the valve and its other end in engagement with 80 a relatively fixed part 14 carried at the forward end of an adjusting screw 15 which is mounted in a threaded opening in the wall of the casing, the outer end of the screw extending to the exterior of the casing and 85 having a suitable adjusting head. The adjusting screw 15 serves to vary the tension of the spring, a lock nut 16 adapted to clamp against the outer wall of the casing being provided to maintain the screw in 90 100 adjusted position.

The valve is adapted to be held open by the gas flowing in the inlet 5 acting in opposition to the force of the spring, the latter operating to force the valve to its seat 105 when the fluid pressure drops below normal or that for which the spring is set to close the valve.

An important feature of the invention resides in the provision of automatic means 110

to lock the valve in its closed position to prevent the opening of the valve by subsequent increase in the gas pressure, so that in the event that lighted burners or the like 5 become extinguished due to fluctuations in the gas pressure, escape of gas from the burners will be prevented, the valve being maintained in closed position until the automatic locking means is released by an at- 10 tendant.

In the particular embodiment of the invention illustrated in the drawings, the automatic locking means comprises a gravity latch 17 pivotally connected intermediate its 15 ends between ears 18 on the under side of the top 19 of the casing. The forward end of the latch 17' is formed to engage the flat upper face 9' of the valve and to coöperate with a shoulder 20 at the upper side of the 20 valve 9 and, in the open position of the valve, rests against the upper flat face thereof in advance of the shoulder 20. When the valve moves to its closed position the end 17' of the latch drops by gravity be- 25 hind the shoulder 20 and securely locks the valve in its closed position. In order to move the latch out of engagement with the valve to release or reset the valve, we provide a push pin or rod 21 arranged to work 30 through an opening 22 in the top of the casing. The rod, which is supported by a coiled spring 23 arranged in a housing 23' on the top 19 of the casing and engaging a collar 24 on the rod, is adapted to be de- 35 pressed to engage and force the inner end 25 of the latch downwardly and swing the forward upper end of the same upwardly out of engagement with the shoulder 20. The rod is provided at its upper end with a 40 suitable push button 26. The top 19 of the casing is removably secured in place in any suitable manner so that ready access is afforded to the interior of the casing.

Any suitable means may be employed to

connect our improved safety device with the 45 gas distributing system.

In the drawings the tubular inlet 5 and the tubular outlet 6 is shown interiorly screw threaded so that the usual threaded union with the pipe sections of the system 50 can be made.

It will be understood that the drawings illustrate a preferred embodiment of the invention and that minor changes in this particular construction and arrangement of 55 parts may be made, within the scope of the appended claims without departing from the nature or principle of the invention.

What we claim is:

1. A safety device including a casing, 60 having an inlet and an outlet, said casing having a dividing wall separating the same into upper and lower compartments, the upper compartment being provided with a flattened inwardly extending valve guide, a 65 reciprocating valve adapted to slide in the said guide, a valve seat, and an automatic latch arranged to lock the valve in its closed position.

2. A safety device comprising a casing, 70 having an inlet and an outlet, said casing having a substantially horizontally arranged partition wall, dividing the same into lower and upper compartments, the upper compartment being provided with a 75 flattened valve guide, a hollow reciprocating valve arranged to slide adjacent said valve guide, a valve seat, and a gravity latch pivotally hung above the valve adapted to lock that element in its closed position.

In testimony whereof we affix our signatures in presence of two witnesses.

FREDRICK D. BOWEN.
SAMUEL T. CLUTTER.
